ALLEN A. TIRRILL, OF PITTSBURGH, PENNSYLVANIA.

ELECTRICAL SWITCH.

1,158,749.

Specification of Letters Patent. Patented Nov. 2, 1915.

Application filed March 28, 1912. Serial No. 888,778.

To all whom it may concern:

Be it known that I, ALLEN A. TIRRILL, a citizen of the United States, and resident of Pittsburgh, in the county of Allegheny and State of Pennsylvania, have invented a new and useful Improvement in Electrical Switches, of which the following is a specification.

My invention relates to electrical switches, 10 and particularly to switches of the rotary snap variety that are employed for controlling lighting and similar circuits.

The object of my invention is to provide an easily operated rotary snap switch of 15 the flush type that is actuated to both its "off" and its "on" positions by means of a single reciprocable push button.

A further object is to provide a position indicator for a snap switch that is mounted 20 separately from the movable switch parts, but is actuated by them. The indicator mechanism is, for that reason, strong, durable and reliable, and permits of an exceedingly compact arrangement of the parts of 25 the switch.

My invention is illustrated in the accompanying drawing, Figure 1 of which is a side and sectional view of a switch that is constructed in accordance therewith. Fig. 30 2 is a face or plan view of the switch of Fig. 1, some of the parts being broken away for the sake of clearness of illustration. Fig. 3 is a side and sectional view of parts of the switch along the line III—III of Fig. 35 2. Fig. 4 is a similar view along the line IV—IV. Fig. 5 is a partial plan or face view, showing parts that are broken away in Fig. 2. Fig. 6 is a side and sectional view of a modification of the indicator that 40 is used in connection with the switch, and Fig. 7 is a face view of a part of the switch showing the said indicator.

The operating parts of the switch are all carried by a frame 1, to which is secured a 45 front plate 2 that covers the switch and the recess in the wall provided for the reception thereof. The frame 1 comprises a base 3 that extends parallel to the front plate and the intermediate portion of which is spaced 50 somewhat from the plate by having its end portions suitably bent. It is also provided

with lateral arms or posts 4 and 5 extending perpendicularly backward from the base and located upon opposite sides thereof, one being preferably formed integral with the 55 base and the other being attached thereto by screws 6.

The arms or posts 4 and 5 are provided near their free ends with apertures for the reception of a shaft 7 that extends between 60 and beyond the sides of the posts. As here shown, one end of the shaft is provided with a bridging member or contact blade 8 that is insulated therefrom, though, if desired, a bridging member may be secured 65 to each end thereof so as to provide a double pole, instead of a single pole, switch. The bridging member is adapted, in certain positions, to engage and electrically connect a pair of separated terminals 9 that are 70 mounted in a porcelain or other suitable insulating box 10 that surrounds and protects the operating parts of the switch, the said box being secured to the frame 1 by 75 bolts 11.

The shaft 7 and the bridging member 8 are adapted to be actuated intermittently, and with a quick or snap action, by means which will now be described, and which comprise an actuating lever 12 carrying a 80 button 13 that projects through apertures in the frame 1 and the plate 2. The said lever is pivoted or fulcrumed to a lateral extension 14 of the post 4, its pivotal axis being quite remote from the axis of the 85 shaft 7, so that a more nearly straight line movement of the operating button, and longer lever arms, are permitted than if the lever were fulcrumed coaxially with the shaft. 90

A pawl 15 is pivotally mounted upon the lever 12, and a spring 16, that is secured at one end to a second lateral extension 17 of the post 4, engages the rear end of the pawl and serves the double function of normally 95 maintaining the lever 12 and the button 13 in the positions shown and of maintaining the hooked end of the pawl in engagement with a ratchet 18. The said ratchet is mounted upon one end of a short sleeve 19 100 that is, in turn, loosely mounted upon the shaft 7, an eccentric 20 being mounted upon

the other end of the sleeve. The sleeve is surrounded between the ratchet and the eccentric by a strong helical spring 21 one end of which is secured to the sleeve, or to one of the parts carried thereby. The other end of the spring engages a lateral boss or extension 22 on a cam plate 23 that is rigidly secured to the shaft, the spring serving to oppose relative movement of the cam plate 10 and the ratchet 18 and to rapidly rotate the cam plate and shaft when they are released. The boss or extension 22 is also adapted to engage a shoulder on the eccentric, it being normally held in engagement therewith by the spring 21.

The cam plate 23 is provided with an aperture comprising a central oblong portion having parallel sides corresponding to and fitting the locally flattened or slotted 20 sides of the shaft 7, and also a circular portion joining the oblong portion at one end, the circular portion being of substantially the same diameter as the main portion of the shaft. In applying the cam plate to 25 the shaft, the shaft is first inserted longitudinally in the circular portion of the aperture and is then moved laterally so that the slotted or flattened portion thereof occupies the oblong portion of the aperture, whereupon a circular plug or key 26 is inserted 30 in the circular portion of the aperture and upset therein to secure the parts together.

The cam plate 23 carries a pawl 27 that is pivotally secured thereto and is provided 35 with a pin 28 that engages the edges of the eccentric 20, the pin and the pawl being actuated by the said eccentric. The pawl 27 engages a ratchet 29 that is rigidly secured to the post 5 and thereby normally serves to 40 lock the shaft in position. However, when it is raised by the rotation of the eccentric 20 until it disengages the teeth of the ratchet, the cam plate 23 and the shaft 7 with the bridging member 8, are rapidly driven forward 45 ward by the spring 21 through the angular distance between the teeth on the ratchet. As the said parts are driven forward the eccentric serves to move the pawl inwardly and to cause it to engage the next tooth on 50 the ratchet 29, the movement being, in this manner, suddenly stopped and the parts being again locked in position. Thus, it is seen, that the pushing in of the button 13 moves the lever 12 and the pawl 15 so as to 55 advance the ratchet 18 and the eccentric 20 and thereby wind up the spring 21. When the eccentric has been sufficiently advanced, the pawl 27 is thereby raised out of engagement with the ratchet 29, and the shaft and 60 its attached parts are rapidly carried forward, the bridging member 8 being caused to rapidly engage or disengage the stationary terminals, as the case may be.

For the purpose of indicating, upon the

exterior of the switch, the positions of the 65 bridging member 8, the plate 2 is provided with a second aperture behind which a movable indicator plate 30 is mounted, the rear face of the plate being slightly recessed for the reception thereof. In Figs. 4 and 5 the 70 indicator plate is reciprocable and is normally maintained in the position shown by a spring 31. It is provided upon its rear face with a projection or boss 32 that is interposed in the path of movement of the 75 ends of the cam plate 23, which are adapted to move the indicator plate to its other position, and to retain it there, against the opposition of the spring 31. When the cam plate is moved to the position shown, the indicator 80 plate is moved by the spring 31 to the position shown. As the indicator plate is mounted separately from the switch parts, and is not rigidly secured thereto, there are no fastening devices therefor to be severed 85 or deranged by the quick movements and sudden stops of the switch parts, and the indicating mechanism is consequently strong, durable and reliable. Also, since it is actuated by simple extensions of the cam plate, 90 which require no additional space longitudinally of the shaft, a very compact structure is provided.

In Figs. 6 and 7 a modified form of the indicator is shown, the indicator plate 33 being circular and adapted to rotate rather than to reciprocate. In this case the cam plate 23 is provided with an arm corresponding to each position of the switch. The positions of the indicator plate 33 are 100 accentuated by the provision of recesses in its edge and a resilient pawl 34 that bears upon its edge and is adapted to enter the recesses.

I claim as my invention:—

1. An electrical switch comprising a shaft, a contact blade carried thereby, a stationary ratchet, a pawl carried by the shaft and adapted to engage with the said ratchet, a second ratchet loosely mounted on the shaft, 110 a cam actuated by the said second ratchet and controlling the said pawl, resilient means interposed between the shaft and the said cam and acting to maintain them in a normal relation to each other, a pawl engaging the said second ratchet, an actuating lever that is fulcrumed eccentrically with respect to the shaft and carries the latter pawl, and a single spring for maintaining the latter pawl in engagement with the said second 120 ratchet and for returning the actuating lever to its initial position.

2. An electrical switch comprising a shaft, a contact blade carried thereby, a stationary ratchet, a pawl carried by the shaft and 125 adapted to engage with the said ratchet, a second ratchet loosely mounted on the shaft, a cam actuated by the said second ratchet

and controlling the said pawl, resilient means interposed between the shaft and the said cam and acting to maintain them in a normal relation to each other, a pawl engaging 5 the said second ratchet, an actuating lever that is fulcrumed eccentrically with respect to the shaft and carries the latter pawl, and means for maintaining the latter pawl in engagement with the said second ratchet and

for returning the actuating lever to its initial 10 position.

In testimony whereof, I have hereunto subscribed my name this 27th day of March, 1912.

ALLEN A. TIRRILL.
